United States Patent Office

Des. 195,756
Patented July 30, 1963

195,756

SIGN

Joseph O. Tally, Jr., Home Federal Bldg.,
Fayetteville, N.C.

Filed Mar. 1, 1963, Ser. No. 73,782

Term of patent 14 years

(Cl. D1—12)

Fig. 1

Fig. 2

Fig. 3

FIG. 1 is a perspective view of a sign showing my new design;

FIG. 2 is an elevational view thereof; and

FIG. 3 is a top plan view thereof.

The broken line representation of letters in FIGS. 1 and 2 is for purposes of illustration only.

I claim:

The ornamental design for a sign, as shown and described.
